UNITED STATES PATENT OFFICE.

FRANK CONRAD, OF SWISSVALE, PENNSYLVANIA. ASSIGNOR TO WESTINGHOUSE ELECTRIC AND MANUFACTURING COMPANY, A CORPORATION OF PENNSYLVANIA.

RADIOTELEGRAPHY SYSTEM.

1,314,789.

Specification of Letters Patent.

Patented Sept. 2, 1919.

Application filed June 5, 1916. Serial No. 101,735.

To all whom it may concern:

Be it known that I, FRANK CONRAD, a citizen of the United States, and a resident of Swissvale, in the county of Allegheny and 5 State of Pennsylvania, have invented a new and useful Improvement in Radiotelegraphy Systems, of which the following is a specification.

My invention relates to systems employed 10 for signaling by means of electric waves that are projected through space without the use of conducting wires.

More particularly, my invention relates to 15 improvements in space-signaling or radio-telegraph systems that embody means for controlling the high-frequency oscillating circuits of such systems without employing interrupters, as keys or key-relays in the main circuits which carry heavy currents 20 and have high self-induction. Such a system has been proposed for use with alternating current generators and ordinary induction coils, the former supplying energy to the high-frequency oscillation circuit, and 25 the latter being utilized for initially ionizing the oscillation producer included in the high-frequency circuit. Since the induction coil cannot be synchronized with the alternating current generator, there is no assurance 30 that the ionization of the spark gap of the oscillation producer will occur at the proper time or the proper point in the alternating current wave of the supply generator to cause the most satisfactory operation of 35 this system.

It is recognized that to render the receiving apparatus of a radio system most effective, the impulses impressed upon the receiving circuit should occur at the rate of 40 about 1,000 impulses per second, which corresponds to the frequency or pitch of a tone of good audibility. To insure uniformity in the production of the tone in the receiving circuit and also the production of a note 45 having a constant pitch, these impulses should be produced at regular as well as frequent intervals. It is apparent, therefore, that the ionization of the spark gap in the high-frequency oscillating circuit should be 50 produced at regular intervals and with a suitable frequency in order to generate and radiate from the antenna a series of wave trains having substantially the same initial amplitudes that will be instrumental in pro-

ducing in the receiving apparatus an audible 55 note of constant pitch or uniform tone.

An object of my present invention, therefore, is to provide means for accomplishing the aforementioned results whereby the radiations emanating from the antenna may be 60 produced at a high rate and at a uniform frequency in order to insure the production of a uniformly-pitched and audible note in the receiving apparatus. I accomplish these results without using a high-frequency alter- 65 nator, but by employing the usual Hertzian oscillation circuit.

For a better understanding of the nature and scope of my invention, reference may be had to the following description and the 70 accompanying drawings in which Figure 1 indicates diagrammatically an arrangement of apparatus employed in connection with a radio-telegraph system that embodies a form of my invention; Fig. 2 is a diagrammatic 75 view showing a modified form of the system shown in Fig. 1; Figs. 3 and 4 are diagrammatic views showing my invention applied to radio-telegraph systems that are fur- 80 nished with energy from two-phase and three-phase power supply circuits, respectively; Fig. 5 is a diagrammatic view showing 85 my invention applied to a radio-telegraph system that embodies means for uniformly producing wave trains of such a frequency as will produce a properly pitched audible note in the associated receiving apparatus; and Figs. 6 and 7 are diagrams to 90 illustrate the operation of the high-fre- 95 quency ionizing circuits of Fig. 5.

In Fig. 1, a direct-current source of power supply 1 is connected by means of conductors 2 and 3 to a condenser 4 which may be of any of the usual types employed in connection with radio-telegraph systems or circuits adapted to produce Hertzian oscillations or electric waves. The condenser 4 by thus being supplied with direct current from a source of adequate power supply is maintained charged to substantially its full capacity at all times excepting at the instants of discharge, as will be hereinafter explained. A suitable inductance device 5 may be placed in circuit with the condenser 4 which will assist in maintaining the regularity of the sparks produced by a spark-producer or electric-wave or oscillation producer 6 associated with the condenser. The 100 105

oscillation producer 6, in this instance, is shown as comprising two pairs of spaced electrodes 7 and 7^a formed of suitable metals or other material, and auxiliary ionizing electrodes 8 and 8^a the function of which will be hereinafter indicated. The high frequency circuit in which the electrical waves or oscillations that are to be projected into space by the radio-system are developed 5 comprises the condenser 4, the oscillation producer 6 and the primary winding 9 of an oscillation transformer 10 which may be of any usual form commonly employed in connection with radio-systems. The second- 10 winding 11 of the oscillation transformer 10 has one of its terminals grounded at 12 and the other connected to an adjustable inductance device 13 which, in turn, is electrically connected to an antenna or elec- 15 tric-wave radiator 14. The windings 9 and 11 may be loosely or closely coupled. It is usually preferable, however, to closely couple these two windings of the oscillation transformer in order to insure that a substantial 20 amount of the energy flowing in the primary circuit will be transferred to the secondary circuit comprising the electric-wave radiator 14. Moreover, the coupling action may be improved if the primary and secondary 25 circuits of the oscillation transformer are in resonance. Again, if proper quenching of the sparks generated by the oscillation producer 6 is effected, the high-frequency oscillations in the primary circuit 30 will discontinue after a very short time interval and the secondary circuit will continue to oscillate at its natural frequency and with its natural damping just as if the primary circuit did not exist. The effectiveness 35 of the radiations emanating from the antenna 14 is, therefore, dependent upon the oscillation decrement of the secondary circuit, the amplitude of the initial vibrations, the rapidity and regularity of the wave 40 trains produced, and the quenching action obtaining in the primary circuit.

To produce high-frequency oscillations in the primary circuit of the oscillation transformer 10, it is necessary to effect discharges 45 at proper times between the electrodes 7 and 7^a. The initial discharges being effected, a very high-frequency oscillating current flows for an instant in the primary circuit by reason of the repeated charging and discharging of the condenser 4. The amplitudes of the high-frequency currents thus generated are constantly decreasing in value because of the damping action of the resistance of the primary and secondary circuits. 50 This is a usual way of generating electromagnetic oscillations that are to be radiated from the antenna of a radio-system. It will be noted that each time one or the other of the spark gaps of the oscillation producer 6 55 is ionized, a wave train is propagated into

space from the antenna 14. Moreover, each one of the wave trains thus emanated produces a single impulse in the receiving apparatus of the associated receiving circuit.

To produce in the receiving apparatus an 70 audible note of proper and uniform pitch, it is desirable to generate in the transmitting circuit, wave trains in the order of 1000 per second which are generated with uniform regularity or frequency in the high-frequency oscillation circuit. To accomplish this, the ionizing electrodes 8 and 8^a are successively energized by means of a control circuit 15 which comprises secondary windings 16 and 16^a of spark coils 17 and 17^a, the corresponding terminals of these windings being connected to the ionizing electrodes 8 and 8^a, respectively, and the other terminals of these coils being connected to corresponding electrodes of the spark 75 gap members of the oscillation producer 6, in this instance the electrodes 7^a. Primary windings 18 and 18^a of the spark coils 17 and 17^a are connected through interrupters 19 and 19^a and an ordinary telegraph key 80 20 to a source of power shown as a battery 21. The source of power 21 may be of relatively small capacity and entirely independent of the energy flowing in the main circuits of the radio-system. Each of the interrupters 19 or 19^a comprises two co-operating contact members 22, the upper one being supported on a spring-actuated member 23, and a rotating cam member 24 which is connected by means of a shaft 25 to any high 85 variable speed propeller, such as a motor (not shown.) The cam members 24 are provided with a series of spaced toothed portions 26 and 26^a which periodically interrupt the respective circuits of the primary windings of the spark coils. The toothed portions 26 and 26^a are so related with one another by reason of the relative displacement of the cam members 24 and 24^a that they alternately actuate with 90 100 regular uniformity the spring members 23 and 23^a of the interrupters, thereby alternately exciting with uniform regularity the primary windings of the spark coils 17 and 17^a when the key 20 is depressed. If the cam members 24 and 24^a are rotated at a proper speed to energize each spark coil at the rate of 500 times or thereabout per second, the energization 105 of the coils being effected alternately, 1,000 110 wave trains per second will emanate from the antenna 14 which insure the production of a uniformly toned and audible note in the receiving apparatus associated with the sending circuits of the figure. Of course, 115 the spark coils 17 and 17^a will be energized during the time only that the key 20 is depressed. Condensers 25^a are connected across the contact members 22 of the interrupters in order to eliminate the sparking 120 125 130

that tends to destroy the active surfaces of the contact members.

To explain the operation of my system more particularly, assume that the condenser 4 has a large electrostatic capacity and that the source of direct current supply 1 is of adequate capacity to substantially instantaneously charge the condenser 4 each time that it discharges by reason of the energization of the spark gaps of the oscillation producer 6. The electrodes 7 and 7^a are spaced a sufficient distance from each other to preclude the occurrence of any discharges between them when subjected to any voltage that may be intentionally impressed on the condenser 4, and while the oscillation producer 6 is uninfluenced by the auxiliary control circuit 15. To generate high-frequency oscillations in the primary circuit of the oscillation transformer 10, it is necessary to effect initial discharges between the electrodes 7 and 7^a in order that the energy stored in the condenser 4 may be transferred in the form of electromagnetic wave trains to the antenna 14 from which they are propagated into space. When the shaft 25 is rotated at the proper speed to insure 500 interruptions or thereabout per second in each of the primary circuits of the spark coils 17 and 17^a, 1000 initial discharges per second are established between the ionizing electrodes 8 and 8^a and the associated electrodes 7^a of the oscillation producer 6, when the key 20 is depressed. The space between each pair of electrodes 7 and 7^a is, consequently, ionized at the rate of 500 times per second which render it conducting to the electric charge contained in the condenser 4. Since the spark gaps are alternately energized, the condenser 4 will, therefore, discharge 1000 times per second, thereby establishing 1000 wave trains which are radiated from the antenna 14. The condenser 4 is recharged to substantially its full capacity during the time intervals existing between the alternate excitation of the ionizing electrodes 8 and 8^a.

It will be noted that the making and breaking of the primary circuits of the spark coils is under complete control by reason of the interrupters 19 and the speed control of the shaft 25. In this manner, a uniformly toned note of audible frequency is produced in the receiving circuit by reason of the uniform and regular production of the wave trains in the main circuit of the transmitting apparatus. Since the condenser 4 is maintained charged or rather instantaneously recharged after each discharge, it is unnecessary to time the energization of the ionizing electrodes 8 and 8^a, such as would be necessary if the condenser 4 were energized from an alternating current source of power supply.

While I have shown the oscillation pro-

ducer 6 as comprising two spark gaps severally associated with spark coils 17 and 17^a, as many spark gaps may be employed as circumstances require. By increasing the number of spark gaps, the rate of making 70 and breaking the primary circuit of each of the spark coils may be decreased in order that the condenser 4 may discharge at the same rate as above indicated. Again, while I have shown the oscillation producer 6 as 75 being composed of stationary spark gap members of the ordinary type, it will be appreciated that any of the well known quenched spark-gap devices may be employed without, in any way, affecting the 80 operation of my system. Similarly, the high-frequency transformer 10 may be dispensed with, the primary circuit being coupled directly with the antenna 14, such as is well known in the art. 85

In Fig. 2, three mercury rectifiers or other asymmetric conductors, 27, 27^a and 27^b, are inserted between a three-phase supply circuit 28 and the condenser 4 in order to furnish it with high-potential rectified currents. 90 The rectifiers 27, 27^a and 27^b are severally associated with the three phases of the supply system 28 and are connected in series with one another in a well known manner. The high-frequency oscillating circuit comprises the condenser 4, a plurality of oscillation producers 6^a, 6^b and 6^c which are connected in parallel, as shown, and an inductive winding 29 by means of which the circuit comprising the condenser 4 and the circuit comprising the antenna 14 are directly coupled. Corresponding electrodes 7^b, 7^c and 7^d of the oscillation producers 6^a, 6^b and 6^c, respectively, are severally associated with ionizing electrodes 8^b, 8^c and 8^d, each of the 105 said ionizing electrodes being respectively connected to secondary windings 16^b, 16^c and 16^d of spark coils 17^b, 17^c and 17^d. The primary windings 18^b, 18^c and 18^d are each respectively connected through interrupters 110 19^b, 19^c and 19^d to the battery 21 and the control key 20. The interrupters 19^b, 19^c and 19^d are each associated with rotatable cams 24^b, 24^c and 24^d that are mounted upon the common shaft 25, the shaft, in turn, being rotated by means of a high variable speed motor 25^b. Projections 26^b, 26^c and 26^d severally associated with the separate cam members 24^b, 24^c and 24^d are so disposed and spaced with respect to one another that, on depressing the key 20, the oscillation producers 6^a, 6^b and 6^c are successively ionized at a very high rate. The rate of discharging the condenser 4 is, therefore, dependent upon the rapidity of ionizing the 125 gaps extending between the three oscillation producers 6^a, 6^b and 6^c.

As mentioned above, the source of power-supply for the condenser 4 is of adequate capacity to substantially instantaneously re- 130

charge the condenser during the time interval existing between successive energizations of the spark gaps in the oscillation producer. The rectified wave impressed upon the condenser 4 by the energizing circuit is of adequate uniformity and renders it unnecessary to time the energization of the oscillation producer so as to have the condenser 4 discharge only at the crests of the waves in the rectified circuit.

The system shown in Fig. 3 contemplates the use of a two-phase energizing circuit and two high-frequency oscillating circuits which are so connected that the oscillations alternately produced in them are impressed upon the circuit comprising the antenna 14. A two-phase alternator 30 supplies power to a transformer 31 and a transformer 32 each of which is shown as being severally connected to one of the phases of the alternator 30. A secondary winding 31^a of the transformer 31 is connected directly across a condenser 33^a and a secondary winding 32^a of the transformer 32 is connected directly across a condenser 33^b. The inductive winding 29 is connected by conductors 34 and 35 to the two high-frequency circuits associated with the secondary windings 31^a and 32^a. One of the terminals of the secondary winding 31^a is connected to the conductor 35 through a pair of oscillation producers 36 and 36^a, and the corresponding terminal of the secondary winding 32^a is likewise connected to the conductor 35 through another pair of oscillation producers 37 and 37^a. In this manner, two high-frequency oscillating circuits are connected across the inductive winding 29, one of said high-frequency oscillating circuits comprising the condenser 33^a and the oscillation producers 36 and 36^a, and the other high-frequency oscillating circuit comprising the condenser 33^b and the oscillation producers 37 and 37^a. Corresponding electrodes of the oscillation producers 36 and 36^a, 37 and 37^a are associated with ionizing electrodes 38 and 38^a, and 39 and 39^a, respectively. Each of the said ionizing electrodes is connected to the secondary or high-tension coil of a spark coil, in such manner as explained in connection with Fig. 1. For example, the ionizing electrode 38 is connected through a conductor 40 to one terminal of the high-tension winding 41 of a spark coil 42, the other terminal of which is connected through a conductor 43 to an associated electrode 36^b of the oscillation producer 36. The primary winding 44 of the spark coil 42 is connected through conductors 45 and 46 to one terminal of the battery 21. The other terminal is connected through a conductor 47, an interrupter 48, a conductor 49 and the sending key 20 to the other terminal of the battery 21. The interrupter 48 is operated by means of a cam

member 50 in the manner heretofore explained in connection with the other systems illustrated. The cam members associated with the several spark coils are displaced with respect to one another so that the spark gaps of the oscillation producers associated with the condensers 33^a and 33^b are ionized at proper times to effect alternate discharge of the condensers 33^a and 33^b.

Since the condensers 33^a and 33^b are energized from the two phases of the two-phase supply circuit, it is necessary to time or rather synchronize the excitation of the oscillation producers so that the condensers 33^a and 33^b will discharge at the proper points in the alternating current waves of the supply circuit, as will be hereinafter explained in detail.

In Fig. 4, I have shown a radio-system supplied with energy from a three-phase power supply circuit 51. A Y-connected primary winding 52 of a three-phase transformer 53 is energized by currents delivered from the circuit 51. Across the phases of a Y-connected high-tension secondary winding 54 are connected condensers 55 that are severally associated with circuits in which high frequency oscillations are successively produced. The condensers 55 are connected in Y-formation to a neutral point 55^a which, in turn, is connected to the neutral point of the secondary winding 54 of the transformer 53 by a conductor 55^b. The condensers 55 are severally associated with oscillation producers 56, corresponding electrodes of which are connected to a common conductor 56^a which, in turn, connects them to the oscillating circuit comprising the antenna 14 and the inductive winding 29. This oscillating circuit is also connected by means of a conductor 56^b to the neutral point 55^a of the condensers. Again, each high frequency oscillator 56 is associated with an ionizing electrode 57, which, in turn, is connected in circuit with its separate spark coil 58. Primary windings 58^a of the spark coils 58 are interrupted in succession and after proper time-intervals by means of rotating cam members 59 associated with interrupters 60. In this manner, the high-potential ionizing currents are generated to initially establish discharges in the oscillation producers 56. It will be noted, therefore, that energy from the three phases of the transformer 53 will be successively impressed upon the antenna circuit 14 which may propagate into space in rapid succession a large number of wave trains for signaling purposes.

In this system, it will be noted by referring to the drawing that each condenser 55 is successively connected in closed circuit with the inductive winding 29 as the corresponding oscillation producers are energized. The condensers 55 are successively energized by the three phases of the supply

circuit 51 and, therefore, it is advisable to time the ionization of the oscillation producers in such a manner that the condensers will discharge when the several alternating 5 current potential waves reach their maximum value. For instance, the ionizing electrodes 57 should preferably be excited twice per cycle of each of the electromotive-force waves of the three-phase supply. This permits 10 of generating of six wave trains during the time of each cycle of each electromotive force wave of the supply circuit. To establish a sufficient number of impulses to generate an audible note in the receiving 15 circuit, the frequency of the alternating current supply should be substantially 166 cycles per second which will generate about 1000 wave trains per second in the high-frequency oscillating circuit.

20 In Fig. 5, I have shown a system whereby 1080 similar wave trains per second may be radiated into space from the antenna of the wireless sending system, while the excitation of the high-frequency circuits is furnished 25 from an ordinary 60-cycle alternating current supply circuit. A transformer 60 has its primary winding 61 connected to supply main 62 which are connected to a source of three-phase currents (not shown). A Y- 30 connected secondary winding 63 of the transformer 60 energizes a plurality of condensers 64 that are connected in Y-formation to a neutral point 65 which, in turn, is connected by means of a conductor 66 to the 35 neutral point of the secondary winding 63. Each of the condensers 64 is associated with a high-frequency oscillation producer 67, the several high-frequency oscillation producers being connected to a neutral point 40 68 that, in turn, is connected to a terminal 69 of the inductive winding 29 which terminates in the antenna 14. The neutral point 65 of the condensers and the energizing winding 63 is connected by means of a conductor 70 to the other terminal of the inductive winding 29 which, in turn, is connected to ground at 71. Each oscillation producer 67 is associated with an ionizing electrode 72. As mentioned above, each 45 50 ionizing electrode 72 is connected to a terminal of a high-tension winding 73 of a spark coil 74, the several secondary windings 73 being connected to a common conductor 75 that, in turn, is connected to the common 55 point 68 of corresponding electrodes of the high-frequency oscillation producers 67. Primary windings 76 of the spark coils 74 have corresponding terminals connected to a common conductor 77 that, in turn, is connected 60 to one side of the battery 21 which, as mentioned above, is utilized to intermittently energize the spark coils 74 when the key 20 in the control circuit 15 is depressed.

A contact-making device 78 comprising 65 a commutating cylinder 79, a rotatable con-

ducting arm 80 and a synchronous motor 81 for propelling said arm is employed to properly time the energization of the ionizing electrodes 72 in order to produce a series of similar wave trains, or wave trains having substantially the same initial amplitudes, in regular succession so that an audible uniformly-toned note may obtain in the receiving circuit associated with this sending system. The commutating cylinder 79 comprises a plurality of uniformly spaced conducting segments 82 that are arranged in six groups, each group consisting of three adjacent segments and oppositely-disposed groups of segments being interconnected 70 with each other, as will be hereinafter explained. The conducting arm 80 is connected to one side of the battery 21 through a slip ring 83 which engages a brush 84. The arm 80 is connected to a shaft 85 of the synchronous motor 81 that, in turn, is connected through leads 86 to the three-phase supply mains 62. In this instance, the motor is so designed as to rotate the conducting arm 80 at the rate of 60 revolutions per 85 second.

The primary windings 76 of the spark coils 74 are severally connected to the proper pairs of segment groups on the commutating cylinder 79; for instance, the primary winding 76^a of the spark coil 74^a is connected to the pair comprising groups 86 and 86^a of the conducting segments 82. The group 86 comprises three adjacent conducting segments which are connected to one another 90 by a conductor 87 and, similarly, the conducting segments of the group 86^a are connected to one another by a conductor 87^a. The oppositely-disposed groups 86 and 86^a are then connected to each other by means 105 of a common conductor 88. In a similar manner, the primary windings of the other spark coils are connected to the other two pairs of groups of conducting segments, as will be observed by referring to the drawing. 110 Since one terminal of the battery 21 is connected to the conducting arm 80 and the other terminal is connected to terminals of the primary windings 76 of the spark coils 74 which, as mentioned above, are connected 115 to the conducting segment 82, it will be apparent that each time the conducting arm 80 engages one of the conducting segments 82, the primary winding of the spark coil associated therewith will be energized and, consequently, as the conducting arm disengages said conducting segment, an electromotive force is induced in the corresponding secondary winding of the spark coil thereby 120 energizing the proper ionizing electrodes 72. 125 In this manner, the ionizing electrodes 72 are energized to initially establish ionizing arcs in the oscillation producers 67 that permit the condensers 64 to discharge through the high - frequency oscillating circuits. 130

Again, by referring to the drawing, it will be observed that each primary winding 76 of the three spark coils 74 is energized three times in succession which energizations are so timed as to occur when the corresponding electromotive force wave of the supply source is near or at its maximum value. By timing the energizations of the primary windings of the three spark coils with regularity, 1080 wave trains per second are emanated from the antenna 14 by reason of the 18 makes-and-breaks being effected in the primary windings of the spark coils during each revolution of the conducting arm 80 which, as mentioned above, rotates at the rate of 60 revolutions per second.

By referring to Fig. 6, I have shown a graphical representation of the three-phase electromotive force waves of the 60-cycle supply circuit. I have also represented time intervals that correspond to twenty electrical degrees by means of equally-spaced perpendicular lines 87. It is my intention to energize the several ionizing electrodes 72 at points in the waves indicated at 90. Both positive and negative halves of the electromotive force waves are utilized since the sign of the discharges is unimportant. Consider the electromotive force wave 88, that is represented by a rotatable vector 88^a of Fig. 7, the positive direction being indicated by the arrow-head. The circuit upon which the electromotive force wave 88 is impressed is ionized by means of the device 79 three successive times as indicated by the lines 91, 91^a and 91^b which are spaced from one another by time intervals corresponding to 20 electrical degrees. After a time interval of 20 electrical degrees, the circuit upon which the electro-motive force wave 92 is impressed is ionized at three successive time intervals represented by the lines 93, 93^a and 93^b. After another time interval of 20 electrical degrees, the circuit upon which the electromotive force wave 98 is impressed is ionized three successive times as represented by the lines 94, 94^a and 94^b. It will be noted from the foregoing description that during each cycle of each electromotive force wave each circuit is interrupted six times and, therefore, from a 60-cycle three-phase circuit 1080 interruptions per second may be effected by means of the device 78 which results in the propagation into space of 1080 wave-trains per second from the antenna 14. Since the initial amplitudes of the high frequency oscillations should correspond to the points 90 in the three electromotive force waves 88, 92 and 96, it may be necessary to impart a phase advancement, or, in other words, to advance the revolving arm 80 slightly in advance of synchronous position in order to ionize the auxiliary electrodes 72 an instant prior to the electromotive force waves reaching their proper values.

Since the electromotive force waves 88, 92 and 96 have substantially the same values at the points indicated by the lines 91, 91^a, and 91^b, 93, 93^a and 93^b, and 94, 94^a and 94^b, respectively, and corresponding points, the initial amplitudes of the wave trains generated in the several high-frequency circuits will be substantially equal in value. Therefore, it is apparent that a properly-toned note of uniform and constant pitch will be obtained in the receiving circuit associated with the transmitting circuit of the figure. In this manner, audible notes are received from circuits energized from an ordinary 60-cycle, three-phase supply circuit. It is necessary, however, that the capacity of the power supply circuit be adequate to substantially instantaneously charge the condensers 64, since they are charged and recharged in very short time intervals.

While I have shown and described several embodiments of my invention, it will be understood that many modifications may be made therein without departing from the spirit and scope of the appended claims.

I claim as my invention:

1. In a system of radio-signaling, the combination with a polyphase supply circuit and high-frequency oscillating circuits severally associated with the phases thereof, of an auxiliary circuit for controlling, in regular and uniform succession, the formation of high-frequency wave trains of oscillations in said high-frequency circuits.

2. In a radio-signaling system, the combination with an electrostatic capacity element, a plurality of high-frequency oscillation producers associated therewith, and an antenna for space-radiating the resultant high-frequency oscillations, of an auxiliary circuit comprising a plurality of ionizing electrodes, spark coils connected thereto, interrupters severally associated with said spark coils, a source of electrical energy, and means for energizing said spark coils in rapid succession and at will, whereby said ionizing electrodes successively influence said high-frequency oscillation producers to establish trains of high-frequency oscillations in rapid succession.

3. In a radio-signaling system, the combination with a polyphase supply circuit, condensers severally associated therewith, a high-frequency oscillation producer associated with each condenser, and an antenna for space-radiating the resulting high-frequency oscillations, of an auxiliary circuit comprising ionizing electrodes severally associated with the oscillation producers of the separate phases of the supply circuit, and means for exciting said ionizing electrodes in succession in the several phases.

4. The combination with a polyphase supply circuit, of high-frequency electrical-oscillation-producing circuits severally as-

sociated with the phases of said polyphase circuit, of an auxiliary circuit controlling the initial production of oscillations in said high-frequency circuits in succession, when properly excited, and means for exciting the auxiliary circuit at will.

5. The combination with a polyphase supply circuit, and a condenser circuit discharging through a high-frequency oscillation producer associated with each phase

of the polyphase circuit, of an auxiliary circuit for initially ionizing said high-frequency oscillation producers in succession, when properly excited, and means for exciting said auxiliary circuit at will.

15

In testimony whereof, I have hereunto subscribed my name this 31st day of May 1916.

FRANK CONRAD.

Copies of this patent may be obtained for five cents each, by addressing the "Commissioner of Patents, Washington, D. C."
